UNITED STATES PATENT OFFICE.

GEORGE L. HUGHES, OF CHICAGO, ILLINOIS, ASSIGNOR OF ONE-HALF TO ROBERT E. COOPER, OF HOPKINSVILLE, KENTUCKY.

POLICE AND FIRE ALARM SYSTEM.

1,105,436.

Specification of Letters Patent.

Patented July 28, 1914.

Application filed February 12, 1913. Serial No. 747,974.

To all whom it may concern:

Be it known that I, GEORGE L. HUGHES, a citizen of the United States, residing at Chicago, in the county of Cook and State 5 of Illinois, have invented certain new and useful Improvements in Police and Fire Alarm Systems; and I do declare the following to be a full, clear, and exact description of the invention, such as will enable 10 others skilled in the art to which it appertains to make and use the same.

This invention relates to improvements in telephone systems and more particularly a police and fire alarm system combined with 15 the ordinary common battery telephone system.

The principal object of this invention is to provide a direct fire or police alarm in connection with a telephone system which 20 may be operated by any subscriber without the intervention of a central operator and which at the same time will give an alarm to such operator or other telephone employee to allow his supervision and assistance if 25 necessary.

Further objects of the invention are to provide a system of this character which will enable the subscriber to obtain a direct connection with the fire or police station 30 quickly so as to make every telephone a fire alarm box and to do this at the least possible cost; to indicate which subscriber's line is calling the special station, that is, the fire or police station, and to lock such connection 35 and thereby enable a call to be traced to its source; to enable the telephone operator to listen and supervise the call to the special station and at the same time not allow such operator to cut off the connection with the 40 special station; to give a distinctive signal, (such for instance, as a red lamp) of call to the special station; and to sound a bell or other audible or visual signal at the telephone central station when the special station 45 is called.

The above and other objects are attained in the embodiment of the invention herein shown and described and by the slight addition of the following parts to the ordinary 50 common battery telephone system, namely: a switch at the subscriber's station to ground the line, a signaling device at the fire station and at the central station, the addition of a differential and oppositely wound relay 55 in connection with the double wound line

relay and audible and visible signals for the telephone operator.

The invention further consists in the various novel features of construction and arrangement hereinafter described and 60 claimed, and illustrated in the accompanying drawings, in which—

Figure 1 is a diagrammatic view of my police and fire alarm system shown in connection with a portion of an ordinary common battery telephone system, the parts being in their normal position; and Fig. 2 is a similar view showing the position of the parts when the subscriber calls the special station such as a fire station or police station. 70

Referring more particularly to the drawings S represents a subscriber's station, C the central station and F the fire or other special station of which there may be any number. 1 and 2 represent the branches of 75 the telephone line connecting the subscriber with central and at the subscriber's station S I have illustrated the ordinary telephone set consisting of the transmitter 3, receiver 4, telephone switch hook 5, polarized call 80 bell 6 and a condenser 7. In addition to these usual parts, the only change which my system entails is the provisions of a suitable switch 9 which may be of any construction such as an ordinary one or two spring 85 push button, a glass covered circuit closure such as commonly used in fire alarm systems, etc.; and the terminals of this switch are connected to ground at 10 and to the branch 1 of the telephone line as shown. 90

11 and 12 represent the branches of the line extending from central to the special station F which latter preferably contains a transmitter 13 and receiver 14 connected in series with the branch 11; a telephone 95 switch hook 15 connected to the branch 12 and adapted when elevated to close the talking circuit through the receiver 14 and transmitter 13 and when depressed by the weight of the receiver to connect onto the 100 branches 11 and 12 by means of conductors 16, 17, the coil of a relay or electromagnetic circuit closure 18. The latter is adapted to close a suitable alarm circuit 19 for the fire station which circuit as here shown embodies 105 an electric fire gong 20 or other suitable signal, a battery 21 and contacts 22 controlled by the armature of the relay 18.

At the central station I have merely illustrated the subscriber's line jack 23, the sub- 110

scriber's line lamp or other signal 24 and an ordinary line relay 25 which latter is of the double coil type including coils O and N. The terminals of the line jack 23 are connected to the telephone line branches 1, 2 and this line jack controls through contact springs 26 of the circuit 27 of the line lamp 24. One branch of the circuit 27 is connected to a battery 28 which latter is grounded at 29 and the other branch of said circuit 27 is connected to ground at 30 through spring contacts 31 controlled by the armature of the line relay 25.

In order to advise the central operator or wire chief or other employee that the fire or other special station has been called I provide a visual signal 32 in the form of an ordinary tell tale lamp and an audible signal 33 such as an electric gong. The latter is included in the circuit 34 containing a battery 35 or other electrical generator and spring contacts 36 controlled by the armature of a relay or electromagnetic circuit closure 37. The armature of this relay 37 also controls the circuit closing contacts 38 of the circuit 39 of the lamp 32. This circuit has one of its branches grounded at 40 through the contacts 38 and its other branch connected to a battery 41 which latter is grounded at 42. I also provide at the central station a differential fire signal and talking relay 43 which has oppositely wound coils F, E and an armature controlling a plurality of pairs of contact springs 44, 45, 46, 47, 48, 49. The contacts 48 and 49 are included in the circuit 50 of the coil of the lamp and bell relay 37 and one branch of this circuit 50 is grounded at 51 through the contacts 48, 49, and the other branch is connected to a battery 52 which latter is grounded at 53. The contacts 46, 47 are connected respectively to the telephone line branch wire 2 and the fire station branch wire 12 while the contacts 44 and 45 are connected respectively to the telephone line branch wire 1 and the fire station branch wire 11 so that the relay 43 when actuated is adapted to close the telephone line 1, 2 of the subscriber onto the line 11, 12 of the fire or other special station and also to close the circuit through the relay 37 which in turn gives the central operator the audible and visual signals to advise that the special station has been called so that such central office employee may plug in at the line jack 23 and listen to the conversation and supervise.

The coils N, O of the line relay 25 and the coils E, F of the special station relay 43 are connected in parallel and the coils E, F are also permanently connected on the main telephone line. This is effected by connecting one terminal of the coil O to the branch 2 of the telephone line at 54 and the other terminal of said coil is connected to a bat-

tery 55 which latter is grounded at 56. From point 54 the branch 2 extends to and is connected to one terminal of the coil E of the special relay 43 and the other terminal of said coil is connected to a battery 57 70 which latter is grounded at 58. The coils N and F of the relays 24, 43 are connected together by a conductor 59 and the other terminals of said coils N, F are grounded at 60 and 61 respectively. The conductor 59 75 is connected between the two relays by a conductor 62 which is connected at 63 to the branch 1 of the main line or telephone circuit so that by means of the switch key or button 9 at the subscriber's station the winding F of the special magnet 43 may be shunted through the ground and the coil N of the line relay 25 may be energized in shunt with the active coil of winding E of the special relay 43. 80

In order to lock the special station relay 43 after it has been actuated in order that malicious fire calls may be traced and punished, any suitable mechanical or electrical locking means may be provided. As illustrated, I have shown a spring catch or lock 64 arranged to engage and hold the armature 65 of the relay 43 when the same has been actuated. This lock must of course be manually released. 85

In operation it will be seen that with the parts in normal position shown in Fig. 1 of the drawings, should a subscriber wish to talk to central or to another subscriber, the telephone system is used in the ordinary 100 manner and since the coils of the special relay 43 are oppositely wound they will neutralize each other and the special station will not be connected to the subscriber. Should the subscriber desire to call the fire 105 or police or other special station he successively or simultaneously removes the receiver 4 from the switch hook 5 and closes the switch 9 which latter shunts the coil winding F of the special relay 43 to ground 110 and permits the coil E to attract the armature 65. This circuit will be as follows: from the battery 57 through coil E, branch 2 of main line through transmitter 3, receiver 4, switch hook 5, branch 1, switch 9 115 to ground and to the negative pole of the battery 57. When the special relay is energized the contacts 44, 45, 46, 47 will connect the main line branches 1, 2 to the fire station branches 11, 12 and the contacts 48, 49 will complete the circuit through the lamp and bell relay 37. The armature of this relay will cause the contacts 36, 38 to close the circuits 34, 39 and thereby sound the bell 33 and illuminate the lamp 32 to 120 advise the central office that a special station has been called. The lock 64 holds the circuits until relay 43 is manually released. When the branches 11, 12 and 1, 2 are connected the relay 18 will be energized to at- 125 130

tract its armature and thereby cause the contacts 22 to close the circuit 19 of the fire gong 20 and thus advise the fire station that a subscriber is calling. When the attendant 5 at the fire station removes the receiver 14 from the switch hook 15 the relay 18 is cut out thereby stopping the fire gong and the talking circuit through the transmitter 13 and receiver 14 is established. The central 10 office, if desired, can plug in at the line jack 23 and listen to the conversation and see that the alarm is properly turned in thereby overcoming the possible failure of the fire chief to receive the alarm should the 15 calling subscriber be confused or unable to properly communicate the alarm.

From the foregoing it will be noted that by the very simple means described and shown the ordinary telephone system may 20 be converted into a very effective fire and police alarm system at extremely small expense since no complicated special apparatus is necessary and the standard telephone equipment can be used and easily connected 25 up. Among the further advantages of my system it will be noted that the telephone operator or other employee cannot cut off the connection between the subscriber and the special station but such operator can 30 listen to and supervise the conversation. A distinctive signal such as a red lamp is given to the special station employee and the latter is advised as to which subscriber is sending in the alarm. Visible and audible signals 35 are given to the telephone central office when the special station is called so that the chief operator or wire chief can have proper supervision.

It will be understood that while I have 40 shown and specifically described one embodiment of my invention that various modifications may be made without departing from the essential features of my invention.

45 What I claim is:

1. In a telephone system, the combination with a central station, and a plurality of subscribers' stations between which communication may be established through the central station; of a differential relay having 50 two coils, one being permanently included in the main line, a switch at the subscriber's station to shunt the other coil through the ground without interrupting the subscriber's circuit, a special station, and means operated by said relay for establishing telephonic communication between the subscriber's station and the special station.

2. In a telephone system, the combination 60 with a central station, and a plurality of subscribers' stations between which communication may be established through the central station, the central station including a double-wound line relay; of a special station, a differential relay for the special

station and provided with oppositely wound coils, wiring connecting the two relays in parallel and permanently connecting the special station relay on the main line, a switch at the subscriber's station for shunting 70 one of the coils of the special station relay through the ground without interrupting the subscriber's circuit, and means operated by said special station relay for establishing telephonic communication between the subscriber's station and the special station. 75

3. In a telephone system, the combination with a central station, and a plurality of subscribers' stations between which communication may be established through the central station; of a differential relay having 80 two coils, one being permanently included in the main line, a switch at the subscriber's station to shunt the other coil through the ground without interrupting 85 the subscriber's circuit, a special station, means operated by said relay for establishing telephonic communication between the subscriber's station and the special station, and means for permanently locking said relay after it has been actuated, whereby it will be retained in actuated position until released manually by an authorized person. 90

4. In a telephone system, the combination with a central station, and a plurality of 95 subscribers' stations between which communication may be established through the central station; of a differential relay having two coils, one being permanently included in the main line, a switch at the subscriber's 100 station to shunt the other coil through the ground without interrupting the subscriber's circuit, a special station, an alarm mechanism at the special station, a movable member operated by said relay for controlling the 105 alarm mechanism and placing the special station in telephonic communication with said subscriber's station when said relay is actuated, and means whereby said removable member can be actuated after communication 110 has been established between central station and subscriber's station.

5. In a telephone system, the combination with a central station and a plurality of subscribers' stations between which communication may be established through the central station, the central station including 115 a double wound line relay; of a special station, a differential relay for the special station having oppositely wound coils, a conductor to connect one of the ends of a coil from each relay, means to connect said conductor to the main line, conductors to ground the opposite ends of the last mentioned coils, batteries for the main line and 120 said relays, said batteries having one of their poles grounded, conductors connecting one of the ends of the other coils of said relays to the remaining poles of said batteries, other conductors connecting the opposite 130

ends of the last mentioned coils to the main line, whereby the two relays are connected in parallel and the special station relay permanently connected to the main line, and
5 means operated by said special station relay for establishing communication between the subscriber's station and the special station.

In testimony whereof I have hereunto set my hand in presence of two subscribing witnesses.

GEORGE L. HUGHES.
